A. M. LASSEN

DRESS SHIELD

Filed Sept. 19, 1923

INVENTOR
Alma Marie Lassen
BY Berg. T. Rauber
her ATTORNEY

UNITED STATES PATENT OFFICE.

ALMA MARIE LASSEN, OF NEW YORK, N. Y.

DRESS SHIELD.

Application filed September 19, 1923. Serial No. 663,525.

To all whom it may concern:

Be it known that I, ALMA MARIE LASSEN, a citizen of the United States, residing at New York, in the county of New York and State of New York, have invented certain new and useful Improvements in Dress Shields, of which the following is a specification.

This invention relates to a dress shield and protector and, more particularly, to an article of apparel by which dresses or skirts of light material may be kept free from the undergarments and from adhering to and otherwise exposing the form of the wearer. Light summer dresses have the disadvantage, owing to their lightness and lack of stiffness, of tending to cling to the wearer, particularly when the wearer rises from a sitting to a standing position. This disadvantage may be overcome to some extent by wearing beneath the skirt or dress a petticoat or a number of petticoats or other garments of relatively heavy, stiff fabric, but in this case, the lightness and coolness desired in summer dresses is sacrificed.

An object of the present invention is to provide a dress shield that will cause the outer dress or skirt to hang naturally and without clinging to, and exposing, the form of the wearer and without sacrificing to any great extent the desired lightness and coolness of the dress.

Another object of the invention is to provide means by which a light, flexible material may be enabled to keep outer garments from clinging to the wearer without materially increasing the weight or heaviness of the material or interfering with the fit or hang of the dress.

Further objects and features of the invention are to provide a dress shield that will not add materially to the bulk of the upper portion of the undergarments, that will provide a shadow screen in the lower portion of the dress, that will remain in position when worn, and that may be rendered moisture proof without interfering with the other features of the garment.

With these and other objects in view, the invention comprises the garment described and set forth in the following specification and claims.

The various features of the invention are illustrated in the accompanying drawings, in which,

Fig. 1 is a view of the garment showing the manner in which it is worn by the wearer, and,

Fig. 2 is a front view of the garment, portions being shown broken away to show the interior construction.

The present application is a continuation in part of my co-pending U. S. application Serial No. 653,093, filed July 23, 1923.

In my present invention, a shield of apron form and of sufficient opacity to prevent the penetration of light rays is suspended dorsally from the waist of the wearer underneath the skirt. This shield has sufficient flexibility to conform sufficiently to the skirt to permit the skirt to hang normally on the wearer and is stiffened in a part of its area, corresponding to the seat portion, by suitable light, stiffening material, such as whalebone, or other stiff material so arranged at said seat portion as to resist the bending on substantially vertical lines of said seat portion, the shield preferably extending a distance on either side of the stiffened seat portion. This stiffening means may be arranged in any suitable configuration and mounted or attached in or to the fabric in any suitable manner and serves to keep this portion of the undergarment separate and free from the form of the wearer and to present a smooth surface to the outer skirt without adding any material extra weight. The upper portion of the garment, lying on the hips of the wearer, is preferably made of reticulated material, such as netting or similar fabric, which affords sufficient strength without adding bulk and thus interfering with the fit of the skirt. To hold the portion of the shield extending past the sides of the stiffened seat portion in a spread out, unfolded position, a pair of short stiffening members are mounted, one at either side of the shield and extend inwardly to a point approximately below the outer edges of the stiffened portion.

Referring more particularly to the accompanying drawings, the shield or protector comprises a sheet of fabric 10 in the form of an apron and of a length sufficient to protect the skirt to the desired length. This fabric may be of any suitable material that will keep the light rays from penetrating through the fabric and outlining the form of the wearer, particularly in the lower portion of the shield. This fabric

may be of any desired color but the color is preferably such as to match that of the skirt or dress worn over it. The protector is suspended or hung from the wearer by means of strings 12 and 14 at its upper corners or by any other suitable means.

In the upper portion of the garment, which fits against the hips of the wearer, and in which portion a shadow screen is unnecessary, the fabric is preferably of reticulated material, such as netting 16 which occupies less bulk and is adapted to fit or conform to the shape of the wearer and thus not interfere with the normal fit of the outer dress, while being of sufficient strength to hold the lower portion of the shield in proper position. The lower edge of the reticulated material to which the fabric 10 is attached may be slightly curved or rounded downwardly to cause the shield to form about the hips of the wearer. To further strengthen this portion of the garment, vertical strips of tape 18 and 20 may be attached to the netting 16 to extend from the lower fabric 10 to an upper hem 22. Both portions 10 and 16 are edges with a hem or edging 24 of tape, lace or other suitable material.

In the central upper portion of the lower fabric 10 are mounted a number of strips 28, 30 and 32 of stiff, resilient material, such as whalebone, three strips being shown by way of example. These strips are preferably arranged substantially parallel and horizontal as, in this position, they offer less interference with the movements of the wearer and are more effective in holding the outer dress free and separate from the undergarments. Other suitable configurations of the stiffening members might be employed, if desired, however.

The pieces or strips of whalebone are mounted on the fabric by means of strips of tape or fabric 34 placed over the pieces of whalebone and stitched along either edge. These strips are preferably extended across the width of the shield for convenience in manufacture and the whalebone later inserted and moved to their proper positions. With the parallel, horizontal arrangement of the whalebone, it is preferable to have the lower pieces of progressively increasing lengths to correspond with the shape of the skirt.

The stiffening means does not extend to the side edges of the garment or past the seat portion to any extent as to do so would make the garment project out flatly and thus interfere with the fit and hang of the outer dress, and would not permit the outer edges or border portion of the garment to conform sufficiently to the shape of the dress. It is desirable, however, that the garment be wider than the area required to be stiffened in order to provide the proper side

support to maintain it in proper position. To prevent this outer side portion of the shield from sagging, wrinkling in or folding, a pair of short pieces of whalebone 36 and 38 are mounted horizontally on the shield 10, one on each side and extending from a point approximately below the outer end of the lowermost strip 32 to the edge of the shield. These strips 36 and 38 are preferably positioned below the strip 32 a distance approximately equal to the spaces between the strips 28, 30, and 32. These strips 36 and 38 accordingly hold the outer side portions of the shield in place without extending the stiffening at the seat portion or otherwise interfering with the flexibility of the shield.

The fabric is thus sufficiently stiffened in the proper interior space to render the outer dress free of the undergarments or wearer without adding any material weight to the garments. This prevents the outer garments from clinging to the wearer, from wrinkling and prevents the transparency of the dresses. It is to be understood that other stiffening means may be employed that has the required lightness, stiffness and resiliency.

To render the outer dress still more independent of, and free from the wearer and to protect them from the effects of perspiration, the fabric of which the shield is formed may be rendered moisture proof by means of a suitable moisture proofing composition that will not impair or detract from the quality of the fabric.

As changes of construction could be made within the scope of my invention, it is desired that all matter contained in the above description or shown in the accompanying drawings shall be interpreted as illustrative and not in a limiting sense.

Having described the invention, what I claim and desire to secure by Letters Patent is:

1. An article of the type described which comprises a piece of fabric of substantially apron form adapted to be worn dorsally, and stiffening material at the part of its area corresponding to the seat portion of said fabric, said stiffening material being so arranged at said seat portion as to resist the bending of said seat portion on substantially vertical lines only.

2. An article of the type described which comprises, a piece of fabric of substantially apron form adapted to be worn dorsally and substantially horizontal strips of stiffening material at the part of its area corresponding to the seat portion of said fabric.

3. An article of the type described which comprises, a piece of fabric of substantially apron form adapted to be worn dorsally having an upper portion of reticulated material and a lower portion of material, and

- transverse strips of stiffening material at the part of its area corresponding to the seat portion of said lower portion.
4. An article of the type described which comprises, a piece of fabric of substantially apron form adapted to be worn dorsally having an upper portion of reticulated material and a lower portion of opaque material and substantially horizontal strips of stiffening material at the part of its area corresponding to the seat portion of said opaque material.
5. An article of the type described which comprises, a piece of fabric of substantially apron form adapted to be worn dorsally having an upper portion of reticulated material and a lower portion of opaque material and substantially horizontal strips of stiffening material at the part of its area corresponding to the seat portion of said opaque material, the length of said strips increasing toward the bottom.
6. An article of the type described which comprises, a piece of fabric of substantially apron form adapted to be worn dorsally, stiffening means at the part of its area corresponding to the seat portion of said fabric, said stiffening means being so arranged as to resist the bending of the said seat portion on substantially vertical lines only, and a pair of independent stiffening means beneath said seat portion and extending from the edges of said apron to a point below the side edges of said seat stiffening means.
7. An article of the type described which comprises, a piece of fabric of substantially apron form adapted to be worn dorsally, substantially horizontal strips of stiffening material at the part of its area corresponding to the seat portion of said fabric and an independent strip of stiffening means extending from beneath either end of said horizontal strips to the adjacent edge of the apron.
8. An article of the type described which comprises, a piece of fabric of substantially apron form adapted to be worn dorsally having an upper portion of reticulated material and a lower portion of opaque material, substantially horizontal strips of stiffening material at the part of its area corresponding to the seat portion of said opaque material, and independent strips of stiffening material extending from beneath either edge of said seat strips horizontally to the adjacent side edges.

In testimony whereof I affix my signature.
ALMA MARIE LASSEN.
